[57] **CLAIM**

The ornamental design for a musical instrument, as shown and described.

DESCRIPTION

FIG. 1 is a top perspective view of a musical instrument showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof.

FIG. 7 is a left side elevational view thereof.

FIG. 8 is a top perspective view of a second embodiment of our new design, the undisclosed front, rear, bottom and side views are similar to those shown in the first embodiment; FIG. 9 is a top perspective view of a third embodiment of our new design.

FIG. 10 is a front elevational view of the embodiment of FIG. 9.

FIG. 11 is a rear elevation view of the embodiment of FIG. 9.

FIG. 12 is a top plan view of the embodiment of FIG. 9.

FIG. 13 is a bottom plan view of the embodiment of FIG. 9.

FIG. 14 is a right side elevational view of the embodiment of FIG. 9.

FIG. 15 is a left side elevational view of the embodiment of FIG. 9.

The broken lines shown are for illustrative purposes only and form no part of the claimed design.
